FIG. - 3

FIG. - 4

FIG. -5

FIG. -6

FIG. 1 is a perspective view of a balloon showing one variation of my new design with the broken line portions omitted for convenience of illustration.

FIG. 2 is a side elevational view of the balloon of FIG. 1;

FIG. 3 is a top or a bottom view, both views being identical, of the balloon of FIG. 1;

FIG. 4 is a perspective view of a balloon showing another variation of my new design with the broken line portions omitted for convenience of illustration;

FIG. 5 is a top or a bottom view, both views being identical, of the balloon of FIG. 4; and

FIG. 6 is a side elevational view of the balloon of FIG. 4.

The dominant features of the design reside in the portions shown in full lines.

I claim:

The ornamental design for a balloon, as shown and described.
